CHARLES NEIL, OF HARTFORD, CONNECTICUT, ASSIGNOR TO THE HART & HEGERMAN MANUFACTURING COMPANY, OF HARTFORD, CONNECTICUT, A CORPORATION OF CONNECTICUT.

ELECTRIC SNAP SWITCH.

Application filed August 14, 1924. Serial No. 731,916.

The objects of the invention relate to simplification of the structure and improvement in the action of electric snap switches, and the invention consists in the several features 5 hereinafter pointed out, especially the feature by which a positive engagement is established between the operating and the operated members to force or help the latter to throw over, and the feature by which 10 the noise of operation is moderated.

In the accompanying drawing, Fig. 1 illustrates an embodiment of the invention, at present preferred, in longitudinal central section. Fig. 2, a section in plan on line 15 II-II of Fig. 1. Fig. 3 a larger scale detail of the operating and operated members in a mid-way position. Fig. 4, the same with the parts in the completely thrown position on line IV-IV. Fig. 5 a section on line 20 V-V of Fig. 4; Fig. 6 is a top plan of the frame. Fig. 7 a large scale detail of the bearing brackets. Fig. 8 a modification of the journal seat. Fig. 9 an enlarged perspective detail of the spring-holding member, and Fig. 10 a perspective of the handle detached.

The switch comprises a porcelain or insulating receptacle which is usual and to which the usual base or frame bar 2 is secured 30 by the screws 3. The receptacle carries fixed therein the two terminal contacts 4 and their respective binding screws, which latter appear in Fig. 2. The center of the frame bar 2 is apertured to accommodate the operating lever or tumbler handle 5 and also the chambered scutcheon 6 which covers up the base of the handle and closes in the space between the same and the frame bar. The frame bar also supports a pair of parallel 35 brackets 7 on its inner side. These are flat stampings and are riveted by their edges to the frame bar adjacent each side of the handle aperture, see Fig. 7, and portions of these brackets project outwardly through or into the frame bar aperture where they are perforated to receive the fulcrum pin 8 on which the operating lever is pivoted.

The brackets 7 are specially shaped with apertures therein which are open to the edge 50 and which constitute journal seats 9 for the carrier 10 of the arm or arms 11 that electrically connect or bridge the fixed contact terminals on the porcelain receptacle. This carrier 10 is the operated member and is in

fact a crank formed of a flat stamping of 55 sheet metal with two rectangular slots 12 punched therein and by means of which it is hooked into the open journal seats 9, so that it pivots on these seats about the center point marked "crank axis" in Fig. 4. 60 The portions of the crank member 10 which constitute its journals and occupy the journal seats 9, may be left flat as punched if desired and as shown, and will turn or rock freely, through the limited arc necessary. 65

The circuit connector or connectors 11 may be attached to one or both ends of the crank member 10 in proper relation for engagement with such terminal contacts as may be located in the receptacle, the form of attachment being electrically insulated so that the crank member does not carry current. 70

The location of the pivot center 8 of the operating lever 5 is selected so that the operating end of the lever projects into the space 75 between the brackets and between shoulders 17 of the crank member 10, and is adapted to oscillate back and forth in this space through or across the plane of the crank. The operating lever is a metal stamping 13. 80 the outer end of which is covered by, or forms the handle means 5, and the inner end of which is punched or slotted, as shown at 14 in Fig. 10, to form a pivotal connection with one end of an intermediate spring- 85 holding member 15, separately shown in enlarged scale in Fig. 9. The other end of this member 15 extends to and straddles and slidingly engages the crank pin part of the crank member 10. The helical spring 16 which it 90 holds in place, surrounds it. One end of the spring thrusts against the shoulders 15^a on the member 15 and the other against the crank member. The spring is thus located between homologous ends or sides of the 95 operating and operated members. When the operating lever is turned on its center 8, in either direction, it carries one end of the spring across the plane of the crank and dead-center line, to a position far enough 100 on the opposite side to cause the spring to snap the crank over to its other position.

The mechanical principle involved is of course well-known in the art. In such movement the spring-holding member 15 accommodates the changing distance between the pivotal point 14 and the crank member by sliding back and forth on the latter; it is 105

a flat stamping twisted 90° on its longitudinal axis and forked to permit this relative movement, but it will be apparent that the spring connection between the operating lever and the crank member can be constructed in various ways to produce the effect described. It is obvious that so far as the operating lever is concerned, it may be made so as to be moved either by means of the lever handle 5, or by push buttons or any other type of actuating or handle means and the necessary modification in the shape of the lever will be understood and applied by those skilled in this art without explanation.

15 The crank shoulders 17 above referred to, being located on the opposite side of the crank axis from the crank-pin portion, and between the crank axis and the frame bar 2 or pivot 8 are proximate to the working 20 end of the operating lever and they accordingly move in the same direction as the proximate end of that lever, whenever the switch is operated from one position to the other. Advantage is taken of this like direction of movement to give the operating 25 lever a positive thrust on the crank member to start it into motion or to throw it over more quickly if for any reason, it should stick or fail to move under the force exerted by the spring. For this purpose the end 30 of the operating lever is provided with the two out-bent fingers 18, one being directed toward one of the shoulders 17 and the other toward the other, and on opposite sides of 35 said shoulders, so that one can serve to push the crank in one direction and the other in the other.

Assuming that the switch is closed, the handle, 5, points to the left and the connector 40 arm 11 bridges the two terminal contacts 4. If now the handle is turned to the right, as for opening the circuit, and if, for example, the connector arm should stick or cling to the contacts 4, the continued movement of 45 the operating lever brings the right-hand finger 18 into contact with the adjacent crank shoulder 17 and by positively pushing thereon throws it over to its other position. Fig. 3 illustrates the engagement of the finger 50 with the crank in the act of pushing the latter over. In this figure, to avoid complication, the spring 16 is represented by a dash line. The dotted line position of the crank member is its circuit-closed position, and as 55 represented by this figure, the crank member may be assumed to have been started and to be on the point of snapping over to its full open position. Obviously the same action occurs when the operating lever is 60 moved in the opposite direction; in that case the left-hand finger 18 will engage the opposite side of the crank member and push it over in the same manner. Inasmuch as the throwing over action depends upon a 65 positive contact between the operating and

operated members, it will be apparent that it is, broadly speaking, immaterial whether the push-over fingers 18 be located on one or the other of these members but preferably they are formed on the operating lever because this is the less expensive construction for this particular type of switch and it is also immaterial, broadly speaking, whether the fingers be pointed one toward one shoulder and one toward the other as shown in 70 the drawing, because it is obvious that they could both engage the same crank shoulder if desired, but again it is found simpler and cheaper to have one finger on each side of the plane of the operating lever, as shown, 75 each engaging the adjacent crank shoulder.

In switches of this class fixed abutments are necessary to stop and limit the movement of the spring-moved parts, in each direction, and the noise of impact is pronounced and for many purposes objectionable. I have discovered that it is practical to reduce this noise by locating the faces of the abutment portions nearer to the center of motion of the member to be stopped, 80 that is to say nearer to its pivot, where its velocity is relatively slow, so that the impact is of a slowly moving surface against a relatively fixed surface. This results in a nearly silent action. In prior switches the abutment has been placed at a considerable distance from the pivot in order to stop the motion without unnecessary strain on the pivots, and the impact has therefore been a high velocity impact and consequently noisy. 85 I find however that the pivots can easily be made to withstand the increased strain, due to location of the abutments close to them, and without any difference in cost. Accordingly, my invention comprehends the location of the active or striking face on the slowest moving part of the mechanism where the noise of impact will be the least. In the simplest embodiment of this part of my invention, the striking and abutment faces 90 are surfaces of the crank member and bearing bracket, respectively, and are immediately adjacent, contiguous, to the crank bearing. They are marked 19 and 20 respectively in Figure 7 and it will be understood that each bracket is similarly shaped 95 so that the movement of the crank member is stopped by its practically simultaneous engagement with the stop faces 19, or 20 as the case may be, of both sides of the frame. 100 By making the brackets of about the thickness of metal indicated I have found they are adequately strong to resist indefinitely the leverage effect.

Fig. 8 illustrates a modification in which each stop face is supplemented by another marked 19^a and 20^a, respectively, on opposite sides of the crank axis. The action will be clear from the figure, it being apparent that in this case four abutment surfaces serve to 105 110 115 120 125 130

stop the movement in each direction and that they are engaged by the slowest moving faces available for motion-stopping use. Obviously the number and size of the faces 5 may be as desired.

The location of the abutments close to the center is particularly suited to a frame and crank construction which incorporates the push-over feature above described, but it will 10 be understood that the noise-reducing feature of this invention is independent of the organization of the switch members and can be embodied in various kinds of snap-action switches, also that the push-over feature can 15 be applied with equal effect to switches having the ordinary location of the abutments, and further that various departures in form and shape and relative arrangement can be resorted to without departing from the principles 20 of this invention as identified and defined in the following claims.

I claim:

1. In a snap switch, a frame bar, an operating lever pivoted on the outer side thereof, a crank member pivoted on the inner side thereof, a throwover spring acting on both members and adapted to initiate the movement of the crank member and proximate aligned portions on said members adapted 30 for positive engagement in the event of the spring failing to effect the said movement of the crank member.

2. In a snap switch, an operating lever, a flat crank member having apertured portions constituting journals, a spring acting 35 between said lever and said crank member on one side of its axis, a shoulder on the crank member on the opposite side of its axis and means for positively engaging said 40 shoulder for moving the crank member.

3. In snap switch, a frame bar, a pair of brackets secured thereto forming hook-form, open journal seats, a flat crank member punched with apertures to be hooked over 45 said brackets and fit in said seats, said bracket forming a throw-limiting abutment for said crank.

4. In a snap switch, a frame bar, a pair of brackets secured thereto and forming hook-form, open journal seats, a crank member formed with apertures to hook over said 50 brackets and fit said seats, said crank member having a portion on the frame bar side of the crank axis adapted to engage said bracket to limit its throw.

5. In a snap switch an apertured frame bar, separately made brackets each secured thereto and each projecting into the aperture and operating and operated members pivoted to said brackets respectively on opposite 80 sides of the bar.

6. In a snap switch, an apertured frame bar, a pair of flat stampings constituting brackets secured thereto and each projecting through the aperture, a handle pivoted to 65 the projecting portions of said brackets and a chambered scutcheon fitting said aperture and closing the space between the bar and handle.

7. In a snap switch an operating lever 70 member, a crank member, a compression spring between the crank and the lever and a holder for said spring formed of a flat stamping twisted at right angles, and forked at one end for sliding engagement 75 with the adjacent member.

8. In a snap switch, a frame bar, a bracket structure secured to the inner face thereof and provided with portions projecting through the bar to the outer side thereof, an 80 operating lever fulcrumed in said projecting portions, a flat stamping constituting a contact-carrying crank journalled by its flat portions in said bracket structure on the opposite side of the frame bar, and a compression 85 spring between the homologous portions of said lever and crank adapted to be carried by the former across the plane of said flat crank.

9. In a snap switch, an apertured frame 90 bar, a pair of similar substantially flat stampings secured to the inner side of said bar and provided with portions projecting through the aperture in said bar, an operating lever pivoted in said stampings on the 95 outer side of said bar and a chambered scutcheon covering said projecting portions.

10. In a snap switch, a frame bar, a bracket structure secured to it, an operating 100 lever fulcrumed thereon adjacent to said bar, a contact-carrying crank journalled in open notches in said bracket structure, more remote from said frame bar, a compression spring between homologous parts of said 105 lever and crank, and abutment surfaces for said crank contiguous to said open notches.

In testimony whereof, I have signed this specification.

CHARLES NEIL.
